UNITED STATES PATENT OFFICE

DONALD D. WHITACRE, OF WAYNESBURG, OHIO

FILTER FLOOR

Application filed October 29, 1927. Serial No. 239,732.

This invention relates to false floor construction or aeration tile for trickle filters used in sewage treatment.

Trickle filters are commonly constructed to comprise a bed of aggregate, which may in a given instance be crushed stone of about 2 inch mesh, through which sewage is allowed to flow and in which bacterial activity causes a "purification" or stabilization of effluent. The bed of aggregate or like material is supported on a false flooring through which the effluent is drained and carried away from the filter. In trickle filters it has been found desirable to make the drains or false floor of clay products, in some instances glazed or vitrified, so that the drains will not become clogged by various growths or solid matter suspended in the sewage. In the spring of the year the bed of the filter tends to clean itself and discharge a relatively high quantity of suspended matter which tends to clog the drains. I find it desirable to make the drain openings large enough so that they may be readily cleaned, if necessary, but I find it of great advantage to construct the drains with a cross section which will tend to accelerate the flow in the bottom portion of the drain so that it will be self cleaning.

It is among the objects of my invention to construct a false floor of channel tile comprising the drains proper and tile grids spanning the channels and supporting the aggregate or filter bed. A further object is to extrude and cut the channel tile to reduce the tendency to warp when burning. Another object is to provide separate load carrying portions on the bottom of the channel tile so that the load may be carried directly by the vertical walls of the tile. A further object is to arrange and construct the grids so that a maximum ratio of passageway or void is provided consistent with necessary strength and minimum thickness. A further object is to conform the size of the grids to the size of the channel tile so that one channel tile and a given number of grids form a complete and independent load carrying unit. Another object is to provide a seat or bed for the grids on the load bearing portions of the supporting tile.

Other objects of my invention will appear from the following description reference being had to the accompanying drawings wherein a preferred form thereof is illustrated. The essential characteristics are summarized in the claims.

Fig. 1 is a fragmentary perspective showing the false floor structure and the filter bed; Fig. 2 is an end elevation of the false floor; Fig. 3 is a partial plan of the floor showing the grid superimposed on the channel tile; Fig. 4 shows the manner of extruding the channel tile; and Fig. 5 is a modified form of the channel tile.

In carrying out the objects of my invention and referring particularly to Fig. 1, I show a concrete floor 1 on which the false flooring is laid. In laying the false floor, it may be found desirable to spread a thin layer of grout or mortar 2 on which the channel tile 3 are set. The channel tile may be laid in parallel rows extending across the bottom of the filter, the filter bottom being slightly inclined in the direction of the channels to facilitate draining.

The tile 3 may be displaced longitudinally relative to each other, if desired, and are laid side by side and end to end to completely cover the floor 1.

Referring also to Fig. 2, I show a channel tile having side walls 4 and a bottom shell 5 and inwardly inclined webs 6, which define the contour of the effluent stream. Suitable voids 7 facilitate burning. The webs and shells may be of less thickness than the load bearing walls 4. As pointed out above, I have found it advantageous to cause the effluent to flow rapidly particularly in the bottom of the channel to carry away sediment or other obstructing matter. With this thought in mind, I cause the surfaces of the webs 6 to define inclined planes as shown in Fig. 2. In Fig. 5, the walls are formed with convex surfaces toward the stream as at 6^a. It will be seen in the first instance that the cross sectional area of the stream decreases at least as rapidly as the depth of the stream, while in the second instance the cross sectional area of the stream decreases more rapidly than the depth of the stream. A chan-

nel of this section tends to maintain or increase the velocity of the stream even when the depth of the stream decreases. In this manner a high fluid velocity is maintained in the bottom of the channel which tends to continually clean it and prevent the collection of suspended matter and the obstruction of the filter.

Referring particularly to Fig. 5, I show a preferred manner of extruding the channel tile, that is, the tiles are extruded in pairs, as at 3^b and 3^c and are dried and burned while joined together, as shown. In the extruding transverse cuts or curfs are made shown at 15 so that the pairs may be separated after they are burned. When the pairs are separated, they are fractured along the lines F, leaving a portion of the top surface of the walls more or less rough. By this procedure I form the tops of the walls 4 with a depressed smooth surface along the curf as at 9 and a relatively raised rough surface along the plane of fracture as at 10. The raised roughened surface 10 serves as a guide or flange for positioning and holding the grids against lateral displacement.

As mentioned above, I employ tile grids 20 which span the channels and I provide a certain number of grids (two are illustrated) for each channel tile. The lateral dimension of the grid may be a little less than the lateral dimension of the channel tile, so that the grid may be seated and accurately positioned on the upper surfaces 9 of the walls 4 and within the fractured surfaces 10. In this manner the grids of laterally adjacent units are spaced apart as at 11, thereby providing a passageway for the effluent between the ends of adjacent grids. The grids 49 may all be of similar size and may be formed to have end walls 21 and side walls 22 (see Fig. 3) with suitable voids 23 through which effluent may descend into the channels. I have found it desirable for grids of given depth that the cross section of all the webs and shells of the grids in a given area constitute about 50% of that area. The grid blocks may preferably have spacing abutments 24 on the side walls (see also Fig. 1) for spacing the blocks apart longitudinally of the drains and for providing openings 25 into the drains from the spaces 11 between laterally adjacent grids.

Referring particularly to Fig. 2, I show that the side walls 4 of the channel tile depend slightly below the bottom surface of the bottom shell 5, and constitute longitudinally extending bearing portions or feet 8. The bearing portions 8 may have flat bottom surfaces between the points EE, and it is advantageous to have these points in vertical alignment with the edges of the upper load bearing surface 9, designated FF. In other words, the points E are in vertical alignment with the points F.

It will appear from the foregoing that a false floor constructed according to my invention comprises a number of independent and self-sustaining units, each of which carries its proportional share of the load of the filter bed. It will further appear that the grids and channel tile are designed to fit together in permanent relative positions and that the load from the grids is carried directly and vertically onto the foundation of the bed; that an economy of grid material is effected by spacing the several grids apart and that the spacings between the grids are effectively used as passageways for effluent. It will further appear that the lateral spacing of the grids is effected by causing the tops of the side walls of the channels to have accurately defined seating surfaces and that such surfaces are arranged in vertical alignment with the bottom load bearing portions of the walls. Channel tile constructed according to my invention provide maximum strength and minimum weight inasmuch as all of the external load is taken through vertical walls so that the remaining webs and shells may be proportionately lighter. It will further appear that drains constructed according to my invention tend to be self-cleaning thereby reducing the operating cost and adding to the efficiency of the filter.

While I have illustrated and described a preferred form of my invention, I do not care to be limited in the scope thereof other than by the claims appended hereto.

I claim:

1. A false floor for trick filters including open drain tile adapted to support laterally extending grid blocks, said drain tile having inclined converging inner walls, a bottom wall and load carrying side walls, joined to said first-named walls, the inner top surfaces of the side walls defining smooth load bearing seats for said grid blocks and the bottoms of side walls forming load carrying extensions vertically aligned with said seats and depending below the bottom wall and holding the bottom wall elevated.

2. In a false floor for trickle filters positioned on a permanent flooring and adapted to carry a filter bed, the combination of drain tile forming open channels and having load carrying side walls, said drain tile being laid side by side and end to end to form parallel channels under said bed, the top surfaces of said side walls comprising an inner and outer portion, the inner portion being smooth and depressed relative to the outer portion, grid blocks spanning the channels and having their ends seated on said smooth inner portions, the ends of laterally adjacent grid blocks being spaced apart above said raised outer portions of the side walls, the load carrying side walls extending below the body of the blocks and forming load carrying feet

vertically aligned with the supported ends of said grid blocks.

3. A false floor for trickle filter comprising open drain tile having load bearing side walls, grid blocks spanning the drains and carried by said side walls, the top surfaces of said side walls having relatively depressed seat portions for the ends of said grid blocks, the bottoms of said side walls extending below the body of said tile and having a load bearing surface, the longitudinal edges of which are in substantial vertical alignment with the longitudinal edges of the said seat portions on the top of the wall and the supported ends of the grid blocks.

4. A false floor for trickle filter formed of separate units, each unit comprising open drain tile having load bearing side walls, and grid blocks spanning the drain and carried by said side walls, the top surfaces of said side walls having relatively depressed seat portions for the ends of said grid blocks, the bottoms of said side walls extending below the body of said tile and having a load bearing surface, the longitudinal edges of which are in vertical alignment with the longitudinal edges of the said seat portions for said grid blocks, each of said drain tile carrying a multiple of whole grid blocks and forming an independent load carrying unit, and projections on the sides of said grid blocks spaced inwardly from the inner edges of the side walls of the drain tile for spacing the grid blocks apart longitudinally.

25 In testimony whereof, I hereunto affix my signature.

DONALD D. WHITACRE.
